ELECTRIC CABLE WINDING AND REELING DEVICE

Julian W. Harris, Tulsa, Okla.

Application January 7, 1936, Serial No. 57,994

1 Claim. (Cl. 15—257)

This invention relates to certain new and useful improvements in electric cable winding and reeling devices, for wheeled electrical or other power driven devices and particularly adapted 5 for use in connection with vacuum cleaners adapted to take up slack in the cable when the vacuum cleaner is being rolled in reverse directions over a rug or surface.

The primary object of this invention is to 10 provide a cable take-up device associated with a vacuum cleaner in such a manner that the cable or a portion thereof will be stored when the vacuum cleaner is being used thereby preventing the cord from becoming entangled with objects such 15 as chairs and tables.

A further object of this invention is to provide 20 traction operating means for reeling and unreeling the electric cable which supplies the vacuum cleaner motor with current from the domestic outlet plug and said means is controllable to establish a direct drive between the traction wheels 25 of the vacuum cleaner and the winding drum or by operating a simple lever the gearing may be disconnected and placed in a neutral position whereby said vacuum cleaner may be rolled across 30 the floor without effecting the winding and reeling of the electric cable.

A further object of this invention is to provide 35 a traversing guide whereby said cable may be evenly wound and unwound upon the drum and said traversing guide is also controllable by the shiftable gearing which connects the traction wheel drive with the reeling and unreeling drum.

A still further object of this invention is to 40 provide a casing or housing for the winding and reeling drum preferably formed of hard rubber or other material having an attractively finished surface which may be conveniently secured to the operating handle of a vacuum cleaner without detracting from the operation or appearance thereof.

A still further object of this invention is to provide 45 means for controlling the operation of the gearing, from a position adjacent and convenient to the handle of the vacuum cleaner within easy reach of the operator whereby reverse motion may be imparted to the winding drum or the same may be disconnected from the traction wheel drive as desired by or at the will of the 50 operator.

Other objects and advantages of the invention will become apparent during the course of the following description, taken with the drawings, wherein,

55 Figure 1 is a perspective view of a vacuum

cleaner illustrating an embodiment of this invention applied thereto;

Figure 2 is a fragmentary sectional view showing the flexible drive shaft between the wheel axle of the vacuum cleaner and the gear mechanism; 5

Figure 3 is a detail sectional view showing the clutch connection between the flexible drive shaft and gear mechanism;

Figure 4 is an enlarged vertical cross-sectional view illustrating the winding and reeling drum 10 and showing the manner in which the same is geared to the flexible traction drive;

Figure 5 is a cross-sectional view taken on line 5—5 of Figure 4, illustrating the electrical connection between the cable and the lead wire 15 connecting the electric motor of the vacuum cleaner;

Figure 6 is a fragmentary cross-sectional view through the casing illustrating in detail the construction of the traversing guide for the purpose of winding and unwinding the electric cable upon 20 the drum;

Figure 7 is a cross-sectional view taken on line 7—7 of Figure 4, illustrating the gear set for engaging the flexible drive with the winding and unwinding drum and said gearing is illustrated as 25 being in its neutral position;

Figure 8 is a similar view illustrating the gear set placed in position for directly connecting the flexible traction wheel drive with the cable winding and reeling drum; and 30

Figure 9 is a transverse cross-sectional view taken on line 9—9 of Figure 4, illustrating the gearing arranged for reversing the drive between the flexible drive shaft and reeling and unreeling drum. 35

In the drawings, wherein for the purpose of illustrating the invention and wherein like reference characters will be employed to designate like parts throughout the same, the reference character 5 will generally be employed to designate a casing preferably formed of hard rubber and the casing is cylindrical and provided at one end with a disk-shaped closure 6. The casing 5 may be secured as by means of a strap band 7 to the handle 8 of a vacuum cleaner A as shown 45 in Figure 1.

The vacuum cleaner A is provided with the usual head 9 adapted to be supported upon the floor by means of rear rollers 10.

The usual dust receiving bag or collector 11 50 is also carried by the handle 8 in a well known conventional manner.

Rotatably mounted within the cylindrical casing 5 is a drum 12 having a reduced portion 13 at one end and a similarly reduced portion 14 at 55

the opposite end and said reduced portions are journalled in bearings 15 and 16 carried by the end walls of the casing 5.

The drum 12 is adapted to have wound thereon a flexible electric cable 17 and one end of the cable is adapted to pass through a slot 18 formed in the wall of the casing and may have its ends provided with an appliance attachment plug for connection with a conventional outlet wall socket.

10 The opposite end of the cable 17 may be fixedly connected to the drum and the conductors 19 and 20 may be electrically connected to collector rings 21 and 22 spaced apart by insulation 23 and 24. As shown in Figure 5, the wires or conductors 19 and 20 extend into the drum through passages formed therein and through the bearing portion 14 in axial bores and connect the connector rings 21 and 22 by lateral connections.

15 Electric communication is established between 20 the cables 19 and 20 and the take-off cables 25 and 26 leading to the electric motor of the vacuum cleaner by means of collector brushes 27 and 28 respectively which have their ends anchored to the detachable head 6 of the casing 5 and their 25 inner ends presented in electric contact with the collector rings 21 and 22. A cover plate 29 houses the cables 25 and 26 and is secured to the detachable head 6 by means of machine screws 30.

Secured to the lower portion of the cylindrical 30 housing 5 is a detachable gear casing 31 having an annular flange 32 for receiving the lower end or bottom of the cylindrical container 5. As shown more clearly in Figures 2 and 3, a tubular boss 33 surrounds an opening and depends centrally from the bottom wall of the gear casing 31 and in which boss a bearing 34 is journalled that has a key socket 34a in its lower end. A flexible shaft 35 is rotatable in the tubular casing 36 and forms communication between the axle 40 support for the rear wheels 10 of the vacuum cleaner and the rotatable bearing 34. The upper end of the flexible shaft 35 has a key portion 35a adapted to be received in the key socket 34a in the bearing 34 and the lower end of the flexible 45 shaft 35 extends through the bearings for the wheels 10 as at 35b with one of the wheels 10 secured as at 35c to the shaft section 35d.

The key portions 35a and 34a constitute clutch elements that are engaged and disengaged with 50 each other by means of a pair of clamp levers 35d pivotally supported as at 35e on a collar 35f fixed to the flexible shaft casing 36, the levers 35d being tensioned as at 35g to move the hook ends 35h thereof into selective reception in spaced 55 notches 35i formed in the outer side of the tubular boss 33.

Rigidly secured to the reduced bearing portion 13 of the drum 12 is a gear 40 which is adapted to be driven by the drive gear 41 secured to the 60 upper end of the bearing 34 and said gears 40 and 41 are connected and adapted to be driven in the same direction by means of an idle gear 42 mounted upon a pin 43 having sliding movement within slots 44 and 44a formed in the bottom 65 wall of the casing 5 and the bottom wall of the gear casing 31 and whereby said idle gear 42 may be moved toward and away from the gears 40 and 41.

Means is provided for shifting the idle gear 70 42 and includes a yoke 45 embracing the idle gear and said yoke is provided with a stem 46 extending through an opening 47 formed in the cylindrical casing 5 and into the handle 8 through an opening 48 and connected to one throw of a 75 crank 49 having the stub shaft 50 journalled

in bearings formed in the handle 8 as at 51. The arm 46 of the yoke 45 is provided with a bearing 52 on one end thereof which encircles the throw 49 so that rotation of the crank 50 will effect the movement of the yoke 45 and cause the idle gear 42 to be moved into and out of mesh with the gears 40 and 41 whereby a direct drive will be established between the flexible shaft 35 and winding and unwinding drum 12.

The crank 50 is provided with a crank throw 10 53 to which is attached a connecting rod 54 as at 55 and the opposite end of the connecting rod 54 is attached to an operating finger piece 56 mounted adjacent the grip portion of the handle 8 as clearly shown in Figure 1. Said finger piece 15 15 operates in a slot 57 formed in the handle 8 adjacent the motor control switch 58 to which may be connected the cables 25 and 26 encased in a housing 58a. The cables may then be connected to the electric motor which is mounted on the 20 suction head of the vacuum cleaner 9.

Reverse gearing is provided for causing the drum 12 to operate or rotate in a reverse direction from the drive shaft 35 and includes a gear 60 adapted to mesh with the gear 41 and such 25 gear 60 is rigidly secured to a shaft 61 on the opposite end of which is provided a smaller gear 62, both gears being mounted in a yoke 63 having slots 64 for receiving the shaft 61. An arm 65 connects the yoke 63 as at 66 to a throw 67 of the 30 crank shaft 50 whereby said yoke 63 may be moved toward and away from the gears 40 and 41. The yoke 63 is extended as at 63' and between the arms of the yoke there is provided a gear 69 mounted on a pin 68 which gear is in 35 mesh with the gear 62 and is adapted to mesh with the gear 40 when the crank 50 is moved by means of the connecting rod 54 to cause the shifting of the yoke with the resultant movement of the gear 69 into engagement with the gear 40. 40 It is to be understood that the gear 62 is smaller in diameter than the gear 60 whereby said gear 60 may mesh with the gear 41 but the gear 62 will not engage the gear 40 so that the shaft 35 may rotate in one direction and the drum 12 45 may be rotated in the opposite direction.

As the finger piece 56 is operated to shift the double gear 42 and reversing gears 60, 62, and 69 toward and away from the gears 40 and 41, either a direct drive may be established between 50 the flexible shaft 35 and drum 12 or the drum 12 may operate or rotate in a reverse direction with respect to the shaft 35. This is necessary when it is desired to wind the cable 17 upon the drum 12 when the vacuum cleaner is being 55 moved toward the outlet plug and after the cleaning operation has been completed and it is desired to store the cable 17 within the casing or housing 5 so that the cleaner may be stored.

The cable 17 may be guided upon the roller 12 60 by means of a traversing guide including a reversing screw shaft 70 having its ends journalled in the bottom wall of the cylindrical casing 5 and the top wall 6 and one end of the reversing screw shaft is provided with a gear 71 adapted 65 to mesh with the gear 41 so that the guide nut 72 may travel from end to end with respect to the reversing screw 70. The guide nut 72 is provided with an arm 73 having an opening 74 for the passage of the flexible cable 17 and the nut 70 72 is retained in place by means of an extension 76 adapted to travel in a longitudinal groove 77 formed in a rib 78 on the interior wall of the casing 5.

As the traversing screw is rotated, the guide 75

nut 72 may strike the end of the casing and be reversed in a fashion well known in the art.

In operation, the free end of the cable 17 may be attached to a wall outlet socket by means of an appliance connection and the switch 58 may be closed to cause current to flow to the motor in the suction cleaner head 9. As the vacuum cleaner A is moved along the surface of the floor rotation is applied to the drive connection between the supporting roller 10 and drum 12 which will cause the cable 17 to be played out and retracted as the cleaner is moved toward and away from the wall outlet plug. This is effected only when the gear 42 is in mesh with the gears 40 and 41 so that there is a direct drive between the flexible shaft 35 and drum 12 and should it be desired to wind the cable 17 within the housing 5 upon the drum 12 after use of the vacuum cleaner, the reverse gearing 62 and 68 may be brought into engagement with the gears 40 and 41 whereby the vacuum cleaner may be moved toward the wall outlet plug or over the floor surface with the result that the cable will be wound upon the drum and stored in the casing 5. If it is desired to operate the vacuum cleaner without employing the use of the drum 12, the finger piece 56 may be operated to cause the direct drive gear 42 and gears 60, 62 and 68 to be moved out of engagement with the gears 40 and 41. When the gears are in the above position, the winding drum 12 becomes inoperative and the cleaner may be used in the conventional fashion. While the

cable take-up device has herein been described as associated with a vacuum cleaner of one type, the invention in its broad aspect may be designed for association with a vacuum cleaner of any character, and may also be used with a wheeled machine, that may be electrically or otherwise driven.

It is to be understood that the form of the invention herewith shown and described is to be taken as the preferred embodiment of the same and that various changes in the shape, size and arrangement of parts may be resorted to without departing from the spirit of the invention or the scope of the subjoined claim.

I claim:—

In combination with a vacuum cleaner or other wheeled electrically driven device having an electric motor, a handle and a supporting wheel, a casing secured to the handle, a cable receiving drum rotatably mounted in the casing, a gear carried by one end of the drum, a drive shaft having one end adjacent the drum gear and adapted to be driven by the supporting wheel, a gear on the drive shaft, direct and reverse driving gears adapted to be moved into and out of engagement with the drive shaft gear and cable drum gear, means on the handle for controlling the movable gears, and a traversing guide parallel with and adjacent to the drum, and a gear on one end of the traversing guide adapted to be driven from the gear on the cable drum.

JULIAN W. HARRIS.
